UNITED STATES PATENT OFFICE.

ARTHUR D. PRATT, OF SHORT HILLS, NEW JERSEY, ASSIGNOR TO THE BABCOCK & WILCOX COMPANY, OF BAYONNE, NEW JERSEY, A CORPORATION OF NEW JERSEY.

STEAM BOILER AND SETTING THEREFOR.

Application filed May 13, 1921. Serial No. 469,167.

To all whom it may concern:

Be it known that I, ARTHUR D. PRATT, a citizen of the United States, residing at Short Hills, in the county of Essex and 5 State of New Jersey, have invented certain new and useful Improvements in a Steam Boiler and Setting Therefor, of which the following is a specification.

My invention more particularly relates to 10 a steam boiler and its setting in which the front upper steam and water drum is spaced from the plane of the front wall. In accordance with my invention provision is made for effectively spanning the space between 15 the top of the wall and the drum.

My invention will best be understood by reference to the accompanying drawings, in which I have illustrated the preferred form thereof, and in which Figure 1 is a vertical 20 section taken through a steam boiler and its setting embodying my invention; Fig. 2 is a front view, partially in section, taken along the line 2—2 of Fig. 1; Fig. 3 is a detail view taken along the line 3—3 of Fig. 4 25 looking in the direction of the arrows, and illustrating the preferred arrangement for suspending the arch between the top of the front wall and the front drum, and Fig. 4 is a section taken along the line 4—4 of Fig. 30 3 looking in the direction of the arrows, and illustrating tiles being strung along the supporting plates.

Like reference characters indicate like parts throughout the drawings.

Referring to the drawings, I have illustrated my invention in connection with a boiler of the Stirling type provided with a lower mud drum 10 connected to front, middle and rear upper steam and water drums 40 11, 12 and 13, respectively, by banks of tubes 14, 15 and 16, over which the gases are directed by baffles 17 and 18 disposed at the rear of the front and middle banks, respectively, and cross baffles 19 and 20 in the last 45 pass, the baffles directing the gases, as indicated by the arrows, to an outlet flue 21. A superheater 22 is preferably disposed between the front and middle banks of tubes, as indicated. The front and middle drums 50 11 and 12 are connected by water circulators 23 and steam circulators 24, and the middle and rear drums 12 and 13 are connected by water circulators 25 and steam circulators 26.

In the form of my invention here illustrated, the front furnace wall, indicated gen-

erally at 27, is located above an underfeed stoker 28 and comprises two sections 27^a and 27^b, the wall extending to the upper portion of the front bank of tubes. The section 27^a is supported by a plate 29 located adjacent to the top ledge of the stoker, as indicated, while the section 27^b, which is offset from the section 27^a and forms a slip joint therewith at 30, is supported on I-beams 31.

Under some conditions, particularly where the wall is formed in sections as illustrated, with the top section offset outwardly from the lower section, the space between the top of the wall 27 and the front steam and water drum 11 is so great that it is not possible to 60 corbel the top of the wall to the steam and water drum in the usual manner. In accordance with my invention, a suspended roof or arch, preferably flat as illustrated and indicated generally at 32, spans the 65

space, or at least a portion of the space, between the top of the wall 27^b and the steam and water drum 11. In the form of my invention here shown, the arch is supported by an I-beam 33 extending across the front 70

of the boiler and supported at its ends in the side walls 34, as indicated in Fig. 2. Supporting plates 35 are, in turn, supported by the I-beam 33, and are preferably provided 75

with notches 36 conforming to the lower 80 flange and lower web portion of the I-beam 33, so that when engaging therewith, as indicated in Figs. 3 and 4, they are supported 85 by the lower flange thereof. Tiles 37 are pro- 90

vided with grooves 38 which engage horizontal flanges 39 formed on the plates 35, which flanges support the tiles, the tiles protecting the supporting metal work from the 95 furnace heat. The lower faces of the tiles at the outer end of the arch rest on the top of the wall 27, the tiles, with the plates 35 on which they are strung, forming a substantially rigid structure, supported on the lower flange of the I-beam 33, and prefer- 100

ably having a limited pivotal movement thereon, so that the outer end of the arch will rise and fall with the wall under differences in expansion between the wall and the boiler, and maintain a seal between the outer end of the arch and the top of the 105 wall, it being understood that the portion of the arch at the right of the beam 33 is heavier than that at the left thereof. The front of the brick roof 40 above the steam and water drum 11 may conveniently be sup- 110

ported from the beam 33, a pad or packing 41 of asbestos or the like preferably being interposed between the upper side of the suspended arch 32 and the lower face of the 5 brick roof 40 coming in front of the steam and water drum 11, to provide for expansion and contraction between the arch and the roof 40.

Brickwork 42 is preferably laid up from 10 a cornice 43 in the upper outer corner of the section 27^b of the wall and extends over the suspended arch, as indicated in Fig. 1. It will be understood that the suspended arch forms a loose joint with the top of the front 15 wall 27.

The upper portion of the section 27^b of the wall may be provided with an opening 44, closed by a door 45, through which tubes, particularly of the front bank, may be renewed. 20

What I claim and desire to secure by Letters Patent of the United States is:

1. A boiler of the general Stirling type, having a front setting wall extending to the 25 upper portion of the front bank of tubes, a roof arch resting on the front setting wall and extending rearwardly from the front wall toward the bank and metallic supports for said arch arranged to allow for relative 30 movement.

2. A boiler of the general Stirling type, having a front setting wall extending to the upper portion of the front bank of tubes, a roof arch resting on the front setting wall 35 and extending rearwardly from the front wall toward the bank, a cross beam and metallic supports suspended therefrom and carrying at least a portion of the roof arch.

3. A boiler of the general Stirling type, 40 having a front setting wall extending to the upper portion of the front bank of tubes, and spaced apart from the front drum to increase the furnace volume, a roof arch resting upon the front setting wall and extending rearwardly from the front wall to 45 toward the bank, and metallic supports for said arch arranged to allow for relative movement.

4. In a steam boiler and its setting, a front 50 furnace wall, a drum spaced horizontally from said wall and having its axis substantially parallel to the face of the wall, a supporting member and a flat arch one end of which is pivotally supported by said member and the opposite end of which rests upon said wall, the rear end of said arch being located adjacent to said drum.

5. In a steam boiler and its setting, a front furnace wall, a drum spaced horizontally 55 from said wall and having its axis substantially parallel to the face of the wall, a supporting member extending parallel to

said drum and a flat arch comprising a plurality of flanged members pivotally supported at one end by said supporting member and at the opposite end supported on said wall, and refractory members carried by said flanged members, the rear end of said arch being located adjacent to said drum. 65

6. In a steam boiler and its setting, a front 70 furnace wall, a drum spaced horizontally from said wall and having its axis substantially parallel to the face of the wall, a supporting member, an arch one end of which is supported by said member and the opposite end of which rests upon said wall and a pad of asbestos or the like for sealing the rear end of said arch against the front drum. 75

7. In a steam boiler and its setting, a front furnace wall, a drum spaced horizontally 80 from said wall and having its axis substantially parallel to the face of the wall, a supporting member, a flat arch one end of which is pivotally supported by said member and the opposite end of which rests upon said wall, a roof located above said drum with its lower edge coming in front thereof and a pad of asbestos or the like interposed between the upper side of said arch and the lower face of said roof. 85

8. In a steam boiler and its setting, a front furnace wall, a drum spaced horizontally 90 from said wall and having its axis substantially parallel to the face of the wall, a supporting member extending parallel to said drum, a flat arch one end of which is pivotally supported by said member and the opposite end of which rests upon said wall, a roof located above said drum with its lower edge located in front thereof and supported on said member, and a pad of asbestos or the like interposed between the upper side of said arch and the lower edge of 95 said roof. 100

9. In a steam boiler and its setting, a front furnace wall, a drum spaced horizontally 105 from said wall and having its axis substantially parallel to the face of said wall, an I-beam extending across the front of the boiler and supported at its ends in the side 110 walls of the setting, a flat arch comprising a plurality of flanged members pivotally supported at one end by said supporting member and at the opposite end supported on said wall, and refractory members carried by said flanged members, the rear end of said arch being located adjacent to said drum, a roof located above said drum with its lower edge discomposed in front thereof and a pad of asbestos or the like interposed 115 between the upper side of said arch and the lower face of said roof. 120

ARTHUR D. PRATT.
